UNITED STATES PATENT OFFICE.

HOWARD COOLIDGE FLEMING, OF WATERTOWN, MASSACHUSETTS.

DOOR-CHECK.

978,870.

Specification of Letters Patent. Patented Dec. 20, 1910.

Application filed May 12, 1910. Serial No. 560,817.

To all whom it may concern:

Be it known that I, HOWARD COOLIDGE FLEMING, a citizen of the United States, residing in Watertown, county of Middlesex, 5 Commonwealth of Massachusetts, have invented certain new and useful Improvements in Door-Checks, of which the following is a specification, reference being had to the drawings accompanying the same and forming 10 a part thereof.

The objects of my invention are to provide a simple device, easily attached to the frame of a door, and adapted to check and prevent the banging of a door in closing, together with other objects which will be set 15 forth in the specification.

In the drawings which accompany this specification and form a part thereof—Figure 1 represents my device attached to sections of a door and door frame; Fig. 2 is a section of a frame of a door and the door with my device attached, with the door closed; Fig. 3 is an enlarged view of the operating portion of my improved door 25 check, showing the checking pawl engaging the notch for checking the forcible closing of the door; and Fig. 4 is a vertical section of my device taken through line 4—4, Fig. 3.

In the drawings, 1 represents a section of a door frame; 2 the rabbet or recess made to receive the edges of the door; 3 a section of a door. The plate 4 is attached to the frame of the door just inside the rabbet or recess 30 to receive the edge of the door, by the screws 5, 5, etc. The swinging door check 6 is pivoted to the plate 4 by the pivot screw 9; and 7 is a spring member secured in the swinging door check 6, provided at its outer end 35 with the curved portion 8 which presents a surface to slip easily upon the door. The stops or pins 10, 10, are secured in the plate 4, their purpose being to limit the swinging movement of the swinging door check 6; 11 40 represents a notch cut in the lower face of the swinging door check 6; and 12 is an angular projection on the lower edge of the swinging check 6, the purpose of which will be explained in connection with the swinging pawl 13 which is pivoted to the plate 4 by a pivot screw 14. The pawl 13 is provided 45 with the angular portion 15 rounded on the end, and adapted to contact with the angular portion 12 of the swinging check 6. 50 The end 16 of the pawl 13 is shaped to fit the notch 11.

The operation of my improved door check is as follows:—The weight of the spring 7 tends to hold the swinging member 6 in a downward position in contact with the stop 10, as shown in Fig. 1. Should the door 3 swing forcibly inward, it will contact with the curved end 8 of the spring 7, and forcibly throw the swinging member 6 upwardly. This forcible throwing of the swinging member 6 upwardly causes the angular portion 12 to violently contact with the angular portion 15 and throw the point 16 upwardly to engage in the notch 11, thus preventing the door from swinging into place in the recess 2, and cushion it by means of the flexibility 65 of the spring 7. The door will rebound slightly from the spring 7 and allow the swinging check 6 to swing downwardly against the stop 10. When the door again 70 contacts with the curved end 8 it will make a slow contact so that the point 12 will swing by the angular portion 15 without throwing the point 16 of the pawl upwardly enough to catch in the notch 11. This movement allows 75 the check 6 to swing upwardly and permit the door to close, as is shown in Fig. 2.

I do not desire to limit myself to the form of the device as shown in the drawings, as modifications of the spring member and 80 plate may be made; in fact the forms of the parts may be materially changed without departing from the spirit of my invention.

Having described my invention, what I claim is—

1. In a door check, a plate; a swinging door check pivoted to the plate; a spring member secured to said swinging door check; and means to engage a notch in said swinging door check to momentarily interrupt its 95 inward swinging movement.

2. In a door check, a plate adapted to be secured to the frame of a door; a swinging door check pivoted to said plate; stops secured in said plate to limit the swinging 100 movement of said door check; a spring secured to the outer end of said swinging door check; and means mounted on the plate to coöperate with the swinging door check to momentarily prevent the swinging movement of said swinging door check should the door forcibly contact with the spring member.

3. In a door check, a plate; a swinging door check pivoted to the plate; a spring 110 member secured to said door check; stops to limit the swinging movement of said door

check; a notch in the lower end of said door check; and an angular portion on said door check adapted to engage with a pawl to cause the pawl to engage said notch should 5 the door forcibly contact with the spring member.

In testimony whereof, I have hereunto set

my hand, in the presence of two subscribing witnesses, this the 28th day of April, A. D. 1910.

HOWARD COOLIDGE FLEMING.
